FIG. 1.

FIG. 2.

FIG. 3.

EDITH H. LOWMAN

By Herman A. Phelps

Attorney

UNITED STATES PATENT OFFICE.

EDITH HILLMAN LOWMAN, OF LOS ANGELES, CALIFORNIA.

BRASSIÈRE.

1,290,608.

Specification of Letters Patent.

Patented Jan. 7, 1919.

Application filed April 10, 1918. Serial No. 227,675.

To all whom it may concern:

Be it known that I, EDITH HILLMAN LOWMAN, a citizen of the United States, residing at Los Angeles, in the county of Los Angeles and State of California, have invented certain new and useful Improvements in Brassières, of which the following is a specification.

The present invention relates to an improved brassière, or corset cover, adapted especially for use as a bust supporter for women's wear.

The primary object of the invention is the provision of a garment of this type in which the breasts are or may be supported from the shoulders of the wearer by the utilization of specially combined features, with special regard to facility in applying or removing the brassière. And to this end the invention resides in a brassière comprising a minimum number of parts that are so related as to be readily adjusted, easily put on or taken off, and providing a device that is comparatively inexpensive in production.

In the accompanying drawings I have illustrated one complete example of the physical embodiment of my invention constructed and arranged according to the best mode I have so far devised for the practical application of the principles of my invention, and this embodiment has proven highly satisfactory in actual use.

Figure 1 is a view illustrating, from the front, the brassière in use.

Fig. 2 is a view at the rear.

Fig. 3 is a view of the brassière spread out flat, showing the outside of the garment.

The belt or band of the brassière which is shown as passing around the wearer comprises three sections 1, 2, and 3, which are preferably of fabric, inelastic, and of proper size and length, the section 2 being at the rear when the garment is worn, and the two outer sections 1 and 3 being at the front.

The two end sections and the intermediate section are joined by elastic webbing, the elastic sections being indicated as 4 and 5, and they are located, when the garment is in use just to the rear of the two sides of the wearer and under the arms.

In the drawings it will readily be seen that

the belt or band is to encircle the upper waist, and be fastened at its ends by the two safety pins 6, 6, which form simple and inexpensive, but efficient means of coupling the two ends together. More elaborate means for fastening the ends together may be employed, but I prefer to use the simple attachments as shown in the drawings, as the pins may be replaced if lost, and the use of the pins permits and insures proper adjustment of the belt about the waist every time it is put on.

The breast supports 7, 7, are in the form of aprons or pouches, of rounded or conical and bulging shape, when flattened out as in Fig. 3, and a pouch is sewed along the top edge of the sections 1 and 3 as shown, so that they will be at the front and in proper position when the garment is on the wearer. Each apron 7 has a strap as 8 sewed at its upper end, and these straps are designed to be crossed, passed over the shoulders as suspender fashion, and attached at the rear to the intermediate inelastic section 2 of the belt, safety pins 9 being also used at the rear, as in the case at the front of the garment.

The garment may be properly adjusted to the wearer by pinning the ends of the straps to the section 2 at the proper point on the straps, thus fitting the straps over the shoulders, and when properly adjusted, the straps may remain attached to the belt section 2, and the garment is put on in the same manner that a vest for men's or women's wear is put on, the hands and arms being passed through the space between the straps, aprons and elastic sections, and then the front sections of the belt brought around to the front and pinned as seen in Fig. 1. The elastic parts 4 and 5 readily adjust themselves to the waist size of the wearer, and the belt forms a rigid and stable anchorage for the garment as it is suspended over the shoulders. The garment is of course made in different sizes, but it will readily be seen that each garment itself is capable of readjustment within limits, as to size and figure of the wearer.

The garment as shown, and actually used, is both comfortable and convenient, as well

as efficient in its use, and provides a serviceable and necessary piece of apparel for women's wear possessing simplicity both in its construction and mode of using.

5 What I claim is:

A brassière comprising a belt formed with end sections and an intermediate section of inelastic fabric and elastic sections joining the end sections with the intermediate sec-

tion, an apron having its edge attached to 10 the end sections, straps attached to the aprons, crossed at the back, and pins attaching the strap ends at the back to the intermediate section, there being suitable fastening means for the adjoining ends of the end 15 sections.

In testimony whereof I affix my signature.
EDITH HILLMAN LOWMAN.
